UNITED STATES PATENT OFFICE.

GEORGE E. SMALL, OF RICHMOND HILL, NEW YORK.

REINFORCED HOLLOW-WALL CONSTRUCTION.

1,214,963.

Specification of Letters Patent.

Patented Feb. 6, 1917.

Application filed May 6, 1915. Serial No. 26,209.

To all whom it may concern:

Be it known that I, GEORGE E. SMALL, a citizen of the United States, residing at Richmond Hill, in the county of Queens and State of New York, have invented certain new and useful Improvements in Reinforced Hollow-Wall Construction, of which the following is a specification.

This invention relates to that class of structures in which the several parts thereof comprising the floors, walls, etc., are constructed of hollow concrete or cement blocks, the object of the invention being to provide an improved construction of reinforced concrete or cement hollow walls in which an improved slab or block of this character is utilized in the building of such a structure.

One of the objects of the invention is the provision of an improved reinforced slab or block which may be manufactured at a very low cost and which, with companion blocks, may be readily assembled and so interlocked one with another that the structure will have the appearance of a monolithic.

Another object of the invention is the provision of improved reinforcing means for the slabs or blocks, which reinforcing means may also be utilized as a means for connecting or locking one block with companion blocks, whereby the several blocks when assembled are so bound together that a very solid reinforced structure is obtained, and by reason of the improved formation of the blocks the structure is provided at intervals with hollow spaces which may be readily utilized for the passage of pipes, conduits etc.

Another object of the invention is the provision of an improved slab or block so constructed and reinforced and provided with improved means for uniting it with companion blocks that such block or slab may be made of great length, so that in many instances it may be of sufficient length to reach the full height of the structure on the outside of the building and the height from floor to ceiling on the inside.

The improved block or slab shown and described herein constitutes the subject-matter of a separate application, Serial No. 50,725, filed September 15, 1915.

In the drawings accompanying and forming part of this specification, Figure 1 is a sectional view illustrating in a general way a side wall, a floor, a ceiling and roof

having this improved construction, the section of the floor, ceiling and side wall being taken through that part of the assembled blocks where a hollow space would be formed; Fig. 2 is a view of one side of one of the slabs or blocks which may be utilized with this improved construction; Fig. 3 is a sectional view illustrating the manner of assembling the slabs shown in Fig. 2 to form hollow reinforced walls; Fig. 4 is an enlarged partly sectional view illustrating a portion of the structure shown in Fig. 3; Fig. 5 is a partly vertical sectional view illustrating the manner in which the blocks are interlocked, and the means for accomplishing this purpose; Fig. 6 illustrates a combined floor and ceiling constructed of these improved slabs; Fig. 7 also illustrates a floor having an attached ceiling in the form of a metal lathing; and Fig. 8 illustrates a ceiling constructed of these improved slabs and having an attached floor.

Similar characters of reference indicate corresponding parts in the several figures of the drawings.

As hereinbefore stated, each of the cement or concrete blocks or slabs 2 will usually be of a length to correspond with the height of the structure, and in Fig. 2 in the present instance the slab is shown of a length about seven and a half times that of its width. It will, of course, be understood, however, that the length of the slab or block will correspond either with the height of the structure or with the distance between the ceiling and the floor and may be made of any length within reasonable limits.

In the preferred form thereof herein shown and described each of the slabs of the form shown in Fig. 2 comprises a pair of oppositely extending wing portions 3 and 4, which may be made, if preferred, of slightly tapered form, which wing portions are united, in the present instance centrally thereof, by a lengthwise extending body or beam portion 5 serving to reinforce the slab or block, and which beam portion is provided at intervals throughout its length with inwardly extending recesses 6, which recesses communicate one with another and with the ends of the block by sections of pipe 12 located in place during the casting of the slab. These recesses 6 are for the reception of the means for interlocking the several slabs together. When slabs of this

form are used for floor construction they may be further reinforced by reinforcing bars 7, 8, see Figs. 4, 6, 7 and 8. These, however, are not necessary when the slabs 5 are used for the construction of side walls. Each of these slabs is at intervals reinforced by the provision of a metal rod or bar 9 extending through the said wings, and certain of these reinforcing rods are located to 10 have the inner ends thereof adjacent to a recess 6 and are so bent as to form a loop 10 extending into such recess 6. These same looped rods at the ends or sides of the slab project therefrom to form loops 11, which 15 loops are of sufficient length to project into the recesses 6 hereinbefore described of companion slabs.

In assembling the several slabs made in the manner described, it will be observed 20 that in Figs. 3 and 4 the outer and inner rows 13 and 14 of slabs break joint with each other and in such manner that the recesses 6 of each slab receives a pair of loops 11 of a companion pair of slabs into overlapping 25 relation with the loop 10, whereby when assembled a locking rod 15 can be inserted through the several sets of loops lengthwise of the slab and thus interlock the several slabs or blocks together. For the purpose of facilitating the insertion of this rod 30 the sectional portions of pipe 12 hereinbefore referred to are located in the slab during the casting thereof and the pipe at each end of the slab may be internally threaded, as at 35 16 for the reception of a lifting eye-plug 17, see Fig. 5, whereby the slab may be readily hoisted into position. As stated, the reinforcing rods 9 are provided with loops at intervals, these intervals corresponding to the 40 position of the recesses 6. At other intervals reinforcing rods may be used, which, however, it is unnecessary to provide with loops. When the walls are assembled at right angles 45 to each other a corner slab 20 of substantially the form shown in Fig. 3 may be used, this corner-slab likewise having a pair of wing portions 21 and 22 meeting in a body portion 23 having rabbeted portions 24 for the reception of the side edges of a pair of outer 50 wall blocks. This corner block is likewise provided with recesses at intervals by means of which the loops of companion blocks may be interlocked with the loop of the reinforcing rod of the corner block in 55 the manner hereinbefore described.

From the foregoing it will be observed that the blocks are so interlocked together that they practically form a unitary structure and also provide hollow spaces between them for 60 the reception of pipes or conduits or any suitable filling material which it may be desired to insert therein. By means of the pipes hereinbefore referred to, after the slabs are assembled grouting may be run into 65 the several recesses, thus making a solid re-

inforced concrete connection and joint, such grouting when in position closing any opening that may exist.

The blocks may be assembled in the manner described to form a floor or ceiling, but, 70 as hereinbefore stated, when utilized as a floor reinforcing bars 7 are preferably used. In Fig. 6 the blocks are shown assembled in the manner hereinbefore described, to form a combined floor and ceiling. In Fig. 75 7, however, an outer row of blocks only is used to form a floor to which is attached a ceiling, such blocks being connected in the same way as shown in Fig. 8, where they form a ceiling to which is attached a floor 80 and have their reinforcing rods twisted together, as at 30, to hold such blocks in position. In both of these instances nailing strips 35 are secured to the concrete or cement blocks by suitable bolts located at intervals, and to these strips may be secured metal lathing, as in Fig. 7, or a wooden floor, as in Fig. 8, the hollow spaces 40 being utilized, as hereinbefore stated, either for the location of gas piping, conduit for 85 electric light wiring, or for the carrying of hot water or air ducts or steam heating appliances if so desired, and these spaces, when the structure is utilized as a floor, may be filled with sand, sawdust, asbestos or any 90 other sound resisting material, thereby providing a sound-proof floor, which is especially desirable in apartments.

In assembling the several slabs to form a wall structure, molding pieces of cement or concrete, such as 50, 60 and 70 may be used, and each of these is likewise reinforced by metal rods 71 having projecting ends 72 so located as to overlap companion blocks, as at 73. In some instances these rods may be 105 twisted together, as at 74.

The height of one floor having been constructed in the manner hereinbefore described, this is repeated throughout the height of the building. The top of the 110 building may be provided with a cornice 80 likewise formed of concrete or cement slabs having a recess 81 for the reception of the upper ends of the side walls, and a downwardly extending leg 82 overlapping the 115 same, thereby to hold the cornice in place, which is preferably insured by a filler of concrete 83, which thus anchors the cornice in place. The cornice is reinforced by metal rods 85 located in the manner shown. Secured to the top of the cornice block as at 84, preferably by being dove-tailed therein, is a wooden strip to which the roof 86 may be fastened.

Of course it will be understood that the 125 outer faces of the walls and faces of the ceilings may be provided with a cement coating or stucco, or the slabs may be pebble dashed when they are first removed from the molds, as may be preferred.

It will also be observed that in each instance the preferable way to maintain and secure the reinforcing rods in position is to provide such reinforcing rods with loops or eyes through which may extend a rod or bar. It will also be understood that the various details may be more or less modified without departing from the spirit and scope of this improvement, which consists mainly in the improved form of cement or concrete block or slab which permits it to be made of great length as compared with its width, and the improved manner of interlocking one slab with companion slabs, whereby a unitary structure is provided and an improved hollow reinforced wall construction obtained.

I claim as my invention:

1. A reinforced hollow wall construction comprising an outer row of slabs or blocks and an inner row of slabs or blocks located to break joint, each of said slabs having reinforcing means provided with projecting eyes or loops at its edges and an intermediate eye or loop projecting horizontally with relation to said slab or block, the eyes or loops of one block adapted to overlap the eyes or loops of companion blocks, a rod for locking said overlapping loops together, and a pipe located in each of said slabs for the passage of said rod.

2. A reinforced hollow wall construction comprising an outer row of slabs or blocks and an inner row of slabs or blocks located to break joint, each of said slabs having a reinforcing beam provided at intervals with recesses, reinforcing means located in each of said blocks and having at the opposite edges thereof projecting eyes or loops and between its edges projecting eyes or loops extending into said recesses, the eyes or loops at the meeting edges of a pair of blocks extending into the recesses in the beam of a companion block, a rod projecting through said loops for locking them together, and a pipe located in each of said slabs for the passage of said rod.

3. A reinforced hollow wall construction comprising an outer row of slabs or blocks and an inner row of slabs or blocks located to break joint, each of said slabs having reinforcing means provided with projecting eyes or loops at its edges and an intermediate eye or loop projecting horizontally with relation to said slab or block, the eyes or loops of one block adapted to overlap the eyes or loops of companion blocks, a rod for locking said overlapping loops together, a pipe located in each of said slabs for the passage of said rod, and a removable plug for the end of said pipe.

4. A reinforced hollow wall construction comprising an outer row of slabs or blocks and an inner row of slabs or blocks located to break joint, each of said slabs having a rein-

forcing beam provided at intervals with recesses, reinforcing means located in said beam and having at the opposite edges thereof projecting eyes or loops and between its edges projecting eyes or loops extending into said recesses, the eyes or loops at the meeting edges of a pair of blocks extending into the recesses in the beam of a companion block, a rod projecting through said loops for locking them together, a pipe located in each of said slabs for the passage of said rod, and a removable plug for the end of said pipe.

5. A reinforced hollow wall construction comprising an outer row of slabs or blocks and an inner row of slabs or blocks located to break joint, each of said slabs having a reinforcing beam provided at intervals with recesses, reinforcing means located in each of said blocks and having at the opposite edges thereof projecting eyes or loops and between its edges projecting eyes or loops extending into said recesses, the eyes or loops at the meeting edges of a pair of blocks extending into the recesses in the beam of a companion block, a rod projecting through said loops for locking them together, and pipe sections located in said beam and communicating with said recesses for the reception of said rod.

6. A reinforced hollow wall construction comprising an outer row of slabs or blocks and an inner row of slabs or blocks located to break joint, each of said slabs having a reinforcing beam provided at intervals with recesses, reinforcing means located in each of said blocks and having at the opposite edges thereof projecting eyes or loops and between its edges projecting eyes or loops extending into said recesses, the eyes or loops at the meeting edges of a pair of blocks extending into the recesses in the beam of a companion block, a rod projecting through said loops for locking them together, pipe sections located in said beam and communicating with said recesses for the reception of said rod, and a removable plug in the end of said pipe.

7. A reinforced hollow wall construction comprising an outer row of slabs or blocks and an inner row of slabs or blocks, the height of each being many times greater than its width and having a beam portion extending throughout its height and located substantially midway of its width, thereby to provide a pair of hollow spaces one at each side of each beam portion, each such beam portion having recesses located at intervals throughout its length, reinforcing means carried by each block and provided with projections extending at each side thereof and also into each of said recesses, the projections at the sides of each block extending into the recesses of companion blocks, and means coöperating with the pro-

jections extending into the recesses for holding the blocks in position.

8. A reinforced hollow wall construction comprising an outer row of slabs or blocks and an inner row of slabs or blocks, each having a beam portion extending throughout its height and located substantially midway of its width thereby to provide a pair of hollow spaces one at each side of each beam portion each such beam portion having recesses located at intervals throughout its length, reinforcing means carried by each block and provided with projections extend-

ing at each side thereof and also into each of said recesses, the projections at the sides of each block extending into the recesses of companion blocks, and means coöperating with the projections extending into the recesses for holding the blocks in position.

Signed at Richmond Hill, in the county of Queens and State of New York, this 1st day of May, 1915.
